EXERCISE DEVICE

George C. Sun, 801 Cooper Landing Road,
Cherry Hill, N.J. 08034

Original design application Mar. 5, 1968, Ser. No. 10,858.
Divided and this application May 22, 1969, Ser. No.
17,283

Term of patent 14 years

Int. Cl. D21—03
U.S. Cl. D34—5

FIG. 2.

FIG. 3.

FIG. 1.

FIG. 1 is a side elevational view of an exercise device embodying my new design;

FIG. 2 is an end view showing the face configuration of the end member;

FIG. 3 is an enlarged sectional view taken on line 3—3 of FIG. 2.

This application is a division of my application Ser. No. 10,858 filed Mar. 5, 1968 and now Pat. No. D. 215,057, entitled "Exercise Device."

I claim:

The ornamental design for exercise device, as shown and described.
